SURFACE TREATING DEVICE

Fredrik Johan Robert Karlström, Stockholm, Sweden, assignor to Inventia Patent-Verwertungs-Gesellschaft, Schaffhausen, Switzerland, a corporation of Sweden

Application July 2, 1932, Serial No. 620,613
In Germany July 6, 1931

19 Claims. (Cl. 91—39)

My invention relates to surface treating devices and more particularly to devices for spreading so-called semi-liquid polishing wax on a floor.

5 The principal object of the invention is to provide a wax distributing device which can be easily manipulated to cause the wax to flow to the floor. A further object of the invention is to provide such a device which is readily controllable by the operator through actuation of a handle.

The principal feature of the invention consists in a rotatably mounted surface contact member which on tilting is caused to rotate and which 15 is attached to or engages a movable member, preferably in the form of a spiral spring, which extends into a wax container or a conduit leading from a wax container to the surface to be treated, the arrangement being such that rotation of the surface contact member causes the spiral member to rotate in the conduit and to cause the wax to be forced toward the surface to be treated.

Further objects and advantages and the nature 25 of the invention will become apparent as the description proceeds, which is to be considered in conjunction with the accompanying drawing showing a number of forms of the invention.

Referring to the drawing:

30 Fig. 1 is a front elevational view of a wax distributing device in accordance with the invention;

Fig. 2 shows the device of Fig. 1 in vertical cross-section;

35 Fig. 3 is a sectional view taken on the line 3—3 of Fig. 2;

Fig. 4 shows a cover for closing the wax container;

Fig. 5 shows the wax distributing device with 40 the cover in place.

Referring to the embodiment shown, the device for distributing wax comprises a receptacle 10 for holding the wax to be applied to the floor. The receptacle 10 is provided with a removable cover 11 and it is provided in the bottom with a centrally disposed opening 13 for allowing wax to pass to the floor. The waxer is equipped with a handle 14 connected to a fork 15 which is pivoted 45 to the container by pivot members 16.

50 The wax may be directly disposed in the receptacle 10 or, as shown in Fig. 2, a can 30 of wax fitting snugly inside the receptacle 10 may be inverted and placed in the receptacle 10. For 55 such an arrangement the receptacle 10 should

be dimensioned to just fit over the size of can as sold on the market.

Within the receptacle 10 and within the can 30, if a can is set into the receptacle, is a member 17 for moving the wax to the outlet 13, which member is preferably in the form of a coil and preferably made of spring metal. Spring 17 fits just inside the outer wall of the wax container and has lower reduced turns in the form of a flat spiral, the lower end of which is connected to 10 an annular disc member designated generally as 25. The upper end of the spring is free. Member 25 is a surface contact member and is rotatably mounted on the lower end of the receptacle 10. The upper part of member 25 is formed 15 by a dish-shaped metal disc 19. In order to mount the member 25 rotationally, the receptacle 10 is grooved and the disc 19 carries a number of spring-pressed balls 21 constituting snap catches whereby the disc 19 is held on the bottom of the receptacle 10 due to the balls 21 entering the groove in the lower part of the receptacle. The groove and balls 21 form a rotatable journal whereby the surface contact member 25 is 20 rotatably mounted on the lower end of the receptacle 10. The disc 19 is equipped with a central opening 20 in alignment with the opening 13 of receptacle 10. The lower surface of the disc 19 is covered by an annular metal plate 22 carrying an annular member 23 of leather, raw hide, 25 or the like. Between the parts 22 and 23 is an insertion 24 of cotton-wool or other soft material. This lower part of member 25 is also apertured in alignment with hole 13.

The handle is provided with a snap catch member 27, which sets into a recess 28 in the cover of the wax receptacle, and which serves to hold the handle in vertical position, while permitting ready release so that the handle may be inclined to push the device.

40 The bottom of the receptacle 10 is preferably provided on its upper surface with grooves 29 arranged tangentially with respect to the opening 13 for facilitating feeding the wax to the opening 13. It will be understood that the spring 17 45 extends through the opening 13 and is secured to the disc 19 so as to be rotatable therewith.

The mode of operation of the device is as follows:

Assume first that the can 30 is not contained 50 within receptacle 10. It will be understood that the spring 17 is within the receptacle 10. The can of wax is inverted and forced downwardly within the receptacle 10 whereby the spring 17 is caused to work upwardly into the wax.

When waxing is to be performed, the device is moved back and forth on the surface to be treated, such as the floor 26. As long as the device is merely moved backwards and forwards, without any twisting motion on the handle, there is no relative movement of the contact member 25 and the receptacle 10. Assume, however, that the handle is twisted so that one side of the member 25 bears harder on the floor than the other side and that the device is moved backwards or forwards. Under this condition the disc 19 will rotate relative to the receptacle 10. This will cause the rotation of the coil spring 17 since this spring is connected rigidly to the disc 19. If rotational movement cannot be obtained merely by excess pressure on one side, the whole device can be tilted as shown in Fig. 1. The disc 19 then forms an angle with the floor, which angle is designated α in Fig. 1, this angle being exaggerated for sake of illustration. On tilting the device as shown in Fig. 1 and moving the device forwards, the spring 17 will be rotated in such manner that the polishing wax will be carried toward the opening 13 and may then be spread on the surface by means of the member 25. When the wax has been forced through the opening 13, the device is righted so that there is an even pressure on the disc 19 and thus the supply of wax stops and the wax forced through the opening 13 can be applied to the floor or other surface by merely moving the device back and forth. Even if the temperature is quite low, the spring 17 can be moved by twisting the handle to loosen the wax and work it down so that it will flow or move to the opening 13.

In order to still more facilitate the travel of the wax to the outlet opening of the wax container, it is preferable to provide the bottom of receptacle 10 with tangential guide slots 29 as shown in Fig. 3. These guide slots or notches 29 prevent the wax from merely sliding along the bottom of the receptacle. The wax is pressed into the slots 29 by the reduced windings at the lower part of the spring and carried in the slots to the opening 13.

Fig. 4 shows a cover 33 for the waxing device for closing the opening 13 when wax is not applied. The cover 33 is provided with a groove 32 adapted to receive spring-pressed balls 31 on the outside of disc 19. On slipping the cover over the bottom of the device, the balls 31 catch into groove 32 and thus the cover is held on. The cover may be, and preferably is, provided with bristles 34 so that with the cover in place the device may be used for polishing the surface to be treated for the application of wax.

It will be understood that one direction of movement is more advantageous in feeding the wax than the other and the operator can readily determine which way to tilt the device to make the wax flow to the opening 13. It will be seen that the coil spring 17 acts like a screw conveyor to work the wax to the outlet opening adjacent the floor.

While I have described a single embodiment of the invention, it will be understood that the invention may be embodied in a number of other forms.

What I claim is:

1. A floor treating device comprising a container for holding wax-like material formed with a discharge opening for the material, a conveyor for discharging said material through said opening comprising a helical strip of small surface area and means for rotating said strip due to

movement of the floor treating device on the floor.

2. A floor treating device comprising a container for holding wax-like material formed with a discharge opening for the material, a conveyor for discharging said material through said opening comprising an open helix providing a large free space in the center for wax-like material in undisturbed condition, and means for rotating said helix due to movement of the floor treating device on the floor. 10

3. A floor treating device comprising a container for holding wax-like material formed with a discharge opening for the material, a conveyor for discharging said material through said opening comprising a helical strip of small surface area disposed within said container close to the inner surface thereof, and means for rotating said strip due to movement of the floor treating device on the floor. 15

4. A floor treating device comprising a container for holding wax-like material formed with a discharge opening for the material, a conveyor for discharging said material through said opening comprising an open helix disposed within said container close to the inner surface thereof and providing a large free space in the center for wax-like material in undisturbed condition, and means for rotating said helix due to movement of the floor treating device on the floor. 20

5. A floor treating device comprising a container for holding wax-like material, said container formed with an opening for the discharge therethrough of said material, a helical member disposed within said container, the surface area of said member being less than the interior surface area of said container, and means for rotating said member due to movement of the floor treating device on the floor to discharge said material through said opening. 30

6. A floor treating device comprising a cylindrical container for holding wax-like material, said container formed with a central opening in the bottom for the discharge therethrough of said material, an open helical member disposed within said container, said member comprising an upper portion of substantially the same diameter as the interior of said container and a lower portion of decreasing diameter approaching the horizontal dimension of said central opening, and means for rotating said member to discharge said material through said opening. 40

7. A floor treating device comprising a container for holding wax-like material formed with a discharge opening for the material, a conveyor for discharging said material through said opening comprising a helical strip of resilient material, and means for rotating said strip due to movement of the floor treating device on the floor. 50

8. A floor treating device comprising a container for holding wax-like material formed with a discharge opening for the material, a conveyor for discharging said material through said opening comprising an open helical strip of resilient material providing a large free space in the center for wax-like material, and means for rotating said strip due to movement of the floor treating device on the floor. 60

9. A surface treating device comprising a container for holding wax-like material formed with a discharge opening for the material, a helical conveyor for discharging said material through said opening, a rotatably mounted surface contacting member adapted to be rotated by movement of said device over a surface, and means 70

75

operatively connecting said conveyor to said member so as to be rotated thereby.

10. A surface treating device comprising a container for holding wax-like material formed with a discharge opening for the material, a conveyor for discharging said material through said opening comprising an open helix providing a large free space in the center for wax-like material in undisturbed condition, a rotatably mounted surface contacting member adapted to be rotated by movement of said device over a surface, and means operatively connecting said conveyor to said member so as to be rotated thereby.

11. A surface treating device comprising a container for holding wax-like material formed with a discharge opening for the material, a conveyor for discharging said material through said opening comprising an open helix disposed within said container close to the inner surface thereof and providing a large free space in the center for wax-like material in undisturbed condition, a rotatably mounted surface contacting member adapted to be rotated by movement of said device over a surface, and means operatively connecting said conveyor to said member so as to be rotated thereby.

12. A surface treating device comprising a container for holding wax-like material formed with a discharge opening for the material, a helical conveyor for discharging said material through said opening, and means connected to said conveyor and operable on tilting said device and moving it over a surface to cause rotation of said conveyor.

13. A surface treating device comprising a container for holding wax-like material formed with a discharge opening for the material, a conveyor for discharging said material through said opening comprising an open helix providing a large free space in the center for wax-like material in undisturbed condition, and means connected with said conveyor and operable on tilting said device and moving it over a surface to cause rotation of said conveyor.

14. A surface treating device comprising a container for holding wax-like material formed with a discharge opening for the material, a conveyor for discharging said material through said opening comprising an open helix disposed within said container close to the inner surface thereof and providing a large free space in the center for wax-like material in undisturbed condition, and means connected to said conveyor and operable on tilting said device and moving it over a surface to cause rotation of said conveyor.

15. A surface treating device comprising a container for holding wax-like material formed with a discharge opening for the material, a helical conveyor for discharging said material through said opening, a circular surface contacting mem-

ber rotatably mounted in a normally horizontal plane beneath said container and adapted to be rotated by tilting said device and moving it over a surface, and means connecting said conveyor to said member so that said conveyor will be rotated thereby.

16. A surface treating device comprising a container for holding wax-like material formed with a discharge opening for the material, a conveyor for discharging said material through said opening comprising an open helix providing a large free space in the center for wax-like material in an undisturbed condition, a circular surface contacting member rotatably mounted in a normally horizontal plane beneath said container and adapted to be rotated by tilting said device and moving it over a surface, and means connecting said conveyor to said member so that said conveyor will be rotated thereby.

17. A floor treating device comprising a cylindrical container for holding wax-like material, said container formed with a central opening in the bottom for the discharge therethrough of said material, an open helical member disposed within said container, said member comprising an upper portion of substantially the same diameter as the interior of said container and a lower portion of decreasing diameter approaching the horizontal dimension of said central opening, and a circular surface contacting member rotatably mounted in a normally horizontal plane beneath said container and adapted to be rotated by tilting said device and moving it over a surface, the lower end of said helical member extending through said opening and being secured to said surface contacting member so as to be rotated therewith.

18. A floor treating device comprising a container for holding wax-like material formed with a discharge opening for the material, a conveyor for discharging said material through said opening comprising an open helix providing a large free space in the center for wax-like material in undisturbed condition, means for rotating said helix, means comprising a cover member adapted to be secured to said container for closing said opening and rendering the rotating means inoperative, and surface treating means carried by said cover member.

19. In a floor treating device, a container for holding wax-like material formed with a central opening in the bottom thereof for the discharge therethrough of said material, a helical conveyor within said container for discharging said material through said opening, and means for rotating said conveyor, the bottom of said container being formed with grooves leading toward said opening for guiding the passage of said material thereto.

FREDRIK JOHAN ROBERT KARLSTRÖM.
